UNITED STATES PATENT OFFICE.

ERNEST G. CLARK, OF DE KALB, ILLINOIS, ASSIGNOR TO CLARK ORCHESTRA ROLL COMPANY, OF DE KALB, ILLINOIS, A CORPORATION OF ILLINOIS.

CORE REINFORCEMENT OF MUSIC ROLLS.

1,407,784.

Specification of Letters Patent. Patented Feb. 28, 1922.

Application filed October 20, 1920. Serial No. 418,219.

To all whom it may concern:

Be it known that I, ERNEST G. CLARK, a citizen of the United States, residing at De Kalb, in the county of De Kalb and State 5 of Illinois, have invented certain new and useful Improvements in Core Reenforcement of Music Rolls, of which the following is a specification, reference being had to the accompanying drawings, forming a 10 part thereof.

The purpose of this invention is to provide an improved spool for carrying the perforated controlling-sheet of an automatic musical instrument, one leading purpose of the invention being to make a more satisfactory spool for that purpose of cheaper construction, including means for reenforcing the core ends thereof and providing such reenforcement with means for 15 mounting and driving the spool and having certain other features, shown and described as pointed out in the claims.

In the drawings:

Figure 1 is a view in part section showing one embodiment of the invention.

Figure 2 is an enlarged view in part section of one end of the same.

Figure 3 is an end view of the spool with the reenforcement applied thereto.

Figure 4 is a view similar to Figure 2 but of a modified form.

Figure 5 is an end view of a portion of the spool with the modified form of reenforcement applied thereto.

In this spool the core or shell, 1, is made of fibre or wood pulp or the like and preferably of comparatively thin stock or material so as not to be excessively heavy, and molded in cylindrical form.

This core, in the course of manufacture is made of indefinite length and prepared for the present purpose by cutting it into lengths of desired dimensions, resulting in a hollow cylinder with open ends.

It is desired to reenforce this cylinder, particularly at the ends and also to form such reenforcing devices so as to provide means for mounting it and the perforated controlling-sheet which is wound upon it,

between the usual supporting and operating spindles.

The reenforcing devices here employed consist of disks, 2—2, of tin or other like metal and centrally apertured at 3 for the 55 reception of the spindles mentioned and

each disk, cup-shaped as shown, has a peripheral flange, 4, of a depth suitable for securing to the end of the shell, 1, and may be glued or cemented in position. The disks or bottoms are as shown, positioned 60 within the shell with the flange, 4, turned outward and terminating flush with the extreme ends thereof, with the bottom innermost; in other words, each disk or bottom is spaced back from the end of the shell a 65 distance equal to the depth of the flange, 4.

The purpose of so positioning the flange, 4, that is outwardly, is to afford space within the boundary of the length of the shell and within the diameter of the flange where 70 in to accommodate means for imparting positively a rotating motion from one of the spindles to the shell. The motion-receiving element, consists of a key or rib struck in from the metal of the reenforcement 75 which is adapted to be engaged by a co-operating part of the driving spindle.

In the form shown in Figures 1, 2 and 3, this rib is produced by forming the flange, 4, with an in-curving portion at 5, while in 80 the modified form shown in Figures 4 and 5 a portion of the metal is struck inward at 6 in the angle formed by the flange, 4^x, and the disk, 2^x. In this form the metal struck in from the disk, 2^x, is designed to substantially equal in depth the extent of intrusion of the key or rib, 5, shown in the 85 previous figures.

In either instance the rib or key is struck out of, and integral with, the reenforcing 90 element.

To further guard the extreme ends of the shell against mutilation in handling, the flange, 4, which extends in the direction of the ends of the core, terminates in a slight 95 radial flange whose extent is substantially equal to the thickness of the material of the shell. This flange further operates as a guide in assembling the parts by limiting the intrusion of the reenforcement in the shell. 100

It will be seen that a music roll spool constructed in accordance with the foregoing description, is economical, practical and easily assembled.

I claim:

1. A music roll core comprising a tubular cylindrical shell, and a reenforcement for the end thereof consisting of a transverse web or disk having a cylindrical marginal flange adapted to telescope into the end of 110

- the shell, and having also an eccentrically-situated abutment for engagement of the rotating means, said abutment projecting into the cavity bounded by the flange.
5. 2. In the construction defined in claim 1, foregoing, the abutment for rotating being situated in the angle between the cylindrical flange and the web of said reenforcing member.
10. 3. In the construction defined in claim 1, foregoing, the reenforcing member being sheet metal and the abutment for rotating being struck inwardly into the cavity bounded by the cylindrical flange.
15. 4. In the construction defined in claim 1, foregoing, the reenforcement being sheet metal and the abutment for driving being struck from the sheet metal inwardly with respect to the cavity bounded by the flange
20. 5. A music roll core comprising a shell, a metallic cup-shaped reenforcement within and at the end thereof, said reenforcement
- consisting of a centrally apertured disk having a circumferential flange projecting at right angles thereto, and a key formed integral with and protruding within said reenforcement at the outer portion thereof.
6. A music roll core comprising a shell, a metallic cup-shaped reenforcement within, and at the end thereof, said reenforcement consisting of a centrally apertured disk having a circumferential flange projecting at right angles thereto, and a key formed integral with and extending within said reenforcement from the outer portion toward the center thereof.
7. A music roll core comprising a shell, a metallic reenforcing disk having an annular flange and a key formed by drawing in a portion of the metal of the flange toward the center of the spool.

In testimony whereof, I have hereunto set my hand at De Kalb, Illinois, this 16th day of October, 1920.

ERNEST G. CLARK.
